DESIGN FOR A COMBINED TRAY AND HOLDER

Joseph F. Hufnagel, Los Angeles, Calif.

Application June 2, 1936, Serial No. 62,968

Term of patent 3½ years

To all whom it may concern:

Be it known that I, Joseph F. Hufnagel, a citizen of the United States, residing at Los Angeles, in the county of Los Angeles and State of California, have invented a new, original, and ornamental Design for a Combined Tray and Holder, of which the following is a specification, reference being had to the accompanying drawing, forming part thereof.

Fig. 1 is a top plan view of the combined tray and holder, showing my new design.

Fig. 2 is a vertical section on line 2—2 of Fig. 1.

I claim:—

The ornamental design for a combined tray and holder, as shown.

JOSEPH F. HUFNAGEL.
